[57]

ABSTRACT

A planar rectangular base member has depending flanges on two opposite sides thereof terminating in spaced opposing in-turned flanges to embrace a support for the base member, an upstanding continuous flange enclosing the top face of said base member and two spaced concentric upstanding hollow ring members secured to said top face for receiving and supporting annular containers therein, such as paint cans, the outer of said concentric ring members extending above said inner ring member and receiving an annular container to be supported upon the top face of said inner ring member. The invention is intended for detachable mounting upon the folding shelf of the conventional step ladder to securely retain paint cans in place and prevent accidental displacement thereof during painting.

CONTAINER SUPPORT AND ATTACHMENT MEANS

BACKGROUND OF THE INVENTION

1. Field of the Invention

The invention is directed to holders for containers such as paint cans and means for detachably mounting said holders upon a step ladder tray or other support.

2. Prior Art

One example of the prior art is found in U.S. Pat. No. 2,982,982 dated May 9, 1961 for Container Support Including Associated Tray Element.

BRIEF SUMMARY OF THE INVENTION

The invention is directed to a container support for detachably mounting upon the customary folding tray of the conventional step ladder and with means for attaching the said support to the step ladder tray.

One object of the invention is to provide an integral support of the character described having spaced inturned flanges to embrace the said step ladder shelf to prevent displacement of the tray.

Another object of the invention is to provide two upstanding spaced concentric ring-shaped portions upon the upper transverse face of the tray to receive paint cans of different capacities, said ring-shaped members being of different diameters to accommodate said different capacity containers.

Another object of the invention is to provide a container support of the character described having peripheral upstanding flanges to retain paint which may have been accidentally discharged over the sides of the containers.

A further object of the invention is to provide means for clamping the tray upon said step ladder shelf.

BRIEF DESCRIPTION OF THE DRAWINGS

FIG. 1 shows a plan view of one form of the invention comprised of formed metal sheets;

FIG. 2 shows a section taken on lines II—II of FIG. 1;

FIG. 3 shows a plan view of an alternate form of the invention comprised of an integrally molded plastic material; and

FIG. 4 shows a transverse section taken on lines IV—IV of FIG. 3.

DETAILED DESCRIPTION OF THE INVENTION

The holder of the invention is adapted to be slidably mounted upon the customary pivotally mounted shelf of a step ladder for the purpose of supporting different sized paint cans during painting ceilings and sidewalls of a room.

For this purpose, the holder indicated generally as 10, comprises a substantially rectangular base member 11 enclosed by an upstanding peripheral flange 12 the free ends of which may be reinforced by flange 13. Underlying said rectangular base member 11 adjacent two opposite sides thereof and secured thereto are two opposing channel-shaped members 14, each comprised of a vertical wall 14a, a top flange 14b and bottom flange 14c, which are spaced to slidably embrace between them the said customary pivotally mounted shelf member (not shown) of a conventional step ladder. As best shown in FIG. 1, the top flanges 14b have slotted openings 14d therein and the base member 11, at opposite sides thereof, has an aperture therein for reception of a bolt whose head 15 abuts flange 14b and whose shank 16 extends through slotted openings 14d and receives a wing nut 17 whereby the two members 14 may be slidably adjusted to embrace the sides of the aforesaid conventional pivotally mounted step ladder shelf (not shown).

Mounted upon the top face of member 11 are concentric upstanding circular flanges 17 and 17a having outstanding bottom flanges 18 and 18a respectively, attached to member

11 by suitable means, such as a rivet 17b. As best shown in FIG. 2, the circular flange 17 is of lesser vertical height than circular flange 17a whereby a smaller paint can, such as quart size, can be received within flange 17 and a larger paint can, such as a gallon size, can be received within flange 17a and supported upon flange 17.

Referring now to FIGS. 3 and 4 of the drawing, wherein a modified form of the invention is shown, comprising an integral molded form of the invention, any suitable molding material may be employed, which will provide sufficient rigidity in the member for receiving and supporting the paint cans as previously described.

As shown in FIGS. 3 and 4 of the drawing, the rectangular base member 111 has integrally formed thereon, upstanding annular central flanges 117 and 117a for reception of quart and gallon size or other size paint cans. The base member 111 is enclosed upon its upper face by the integral rectangular upstanding flange 112 and is defined on two opposite sides thereof by depending integral spaced angular flanges 114 for embracing the sides of the customary pivotally mounted step ladder shelf (not shown).

I claim:

1. A container support for detachably mounting upon a customary folding shelf of a conventional step ladder, comprising a rectangular pan-shaped member having a planar bottom wall enclosed by upstanding rigid sidewalls and connecting rigid end walls; a first annular upstanding member fixed upon said pan-shaped member bottom wall and extending above said pan-shaped member sidewalls; a second annular 25 upstanding member of lesser vertical height and diameter mounted upon said pan-shaped member bottom wall within said first annular member and rigidly connected to said bottom wall; the vertical height of said first annular member being such that a container received thereby and resting on 30 said second annular member is stably supported against transverse displacement or tilting by said first annular member; and inturned members connected at two opposite sides of said pan-shaped member and extending downwardly therefrom for receiving a ladder folding shelf therebetween.

40 2. The container support as defined in claim 1 wherein at least one of said inturned members has an inturned top flange underlying said rectangular pan-shaped member bottom wall in abutting engagement therewith with a slotted opening formed in said underlying inturned top flange; and means connecting said inturned flange to said planar bottom wall for adjustably clamping said container support to said ladder folding shelf.

3. The container support as defined in claim 1, wherein said second annular member is concentrically disposed within said 45 first annular member.

4. A container support of the character described, in combination, a rectangular vertically disposed rigid flange, a rectangular transverse wall integral with the inner faces of the walls of said vertically disposed flange intermediate the vertical height thereof, a first annular vertically disposed flange integral with said transverse wall and extending thereabove, a second annular vertically disposed flange integral with said rectangular transverse wall and enclosing said first annular vertical wall in spaced relation thereto and extending 55 thereabove, each said annular flanges being of a suitable height to restrain a container received therein against transverse displacement or tilting and said container received within said second annular flange being supported upon the top surface of said first-named annular flange, and said first-named rectangular vertically disposed flange having upon two opposite sides thereof inturned bottom horizontal flanges for embracing a ladder member providing vertical support for said container support and the container disposed therewithin.
